Primary Examiner — Susan Bennett Hattan(74) *Attorney, Agent, or Firm* — Husch & Blackwell LLP; H. Frederick Rusche(57) **CLAIM**

We claim the ornamental design for a bottle insert, as shown and described.

DESCRIPTION

FIG. 1 is a perspective view of a bottle insert showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof showing said bottle insert in the neck of a bottle.

The broken lines shown in the drawing views are included for the purpose of showing environmental structure that forms no part of the claimed design.
